UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed August 4, 1925. Serial No. 48,039.

To all whom it may concern:

Be it known that I, ERNEST L. TEICH, a citizen of the United States, residing at New Britain, county of Hartford, State of Connecticut, have invented a certain new and useful Improvement in Locks, of which the following is a full, clear, and exact description.

My invention relates to locks and has for its object to provide a lock which is capable of functioning the same as any one of a number of different types of locks as heretofore constructed, thus requiring the manufacturer to make, or dealer to carry in stock locks of but a single type instead of a number of different types. It further has for its object to secure this advantage in a lock which is adapted for use on either right or left hand doors.

The several features of the invention, whereby the above mentioned and other objects may be attained, will be clearly understood from the following description and accompanying drawings, in which,

Fig. 1 is a side view of my improved lock with a portion of the cover of the casing broken away;

Fig. 2 is a sectional view taken substantially on the line 2—2 of Fig. 1 and showing one of the knobs of the lock by broken lines;

Fig. 3 is a sectional view, partly in elevation, taken on line 3—3 of Fig. 1;

Fig. 4 is a detail sectional view taken substantially on the line 4—4 of Fig. 1;

Figs. 5 and 6 are views similar to Fig. 4, but on an enlarged scale and showing different arrangements of certain parts of the lock;

Fig. 7 is a side view of the parts shown in Fig. 6, but with the cover of the casing and with one of the shanks of the knobs of the lock removed;

Fig. 8 is a detail view in perspective of one of the latch bolt operating hubs, forming a component part of the lock; and

Fig. 9 is a detail view in perspective of a stop member forming a component part of the lock.

The lock illustrated in the drawings is provided with a case 2 having a cover 4 secured thereon by screws 6, and a face-plate 8 secured on the front edge thereof. The lock is further provided with a lock bolt 10

and a pin tumbler lock 12 having a roll back 14 which is adapted to be actuated to project and retract the bolt. The cylinder or casing of the pin tumbler lock is screw-threaded through an aperture 16 in one side of the casing, there being an aperture in both sides of the casing so as to permit the pin tumbler lock to be applied to either side thereof. The lock is further provided with a latch bolt 20 which is pressed outwardly by means of a spring 22 coiled about the stem 24 of the bolt and interposed between the head of the bolt and a washer 26 that bears against a lug 28 integral with the lock case, said lug having a groove or slot through which said bolt stem extends. A rectangular abutment plate 30 is secured on the rear end of the latch bolt stem, and one arm of a bell-crank 32 extends between the slotted lug 28 and the abutment plate 30. The other arm of the bell-crank 32 is arranged to be engaged by a block or bar 34 mounted to slide transversely on the lock bolt 10, and adapted to be actuated by the roll back 14 to act through the bell-crank 32 and the abutment plate 30 to retract the latch bolt. The latch bolt is adapted to be reversed in position in the lock. The lock is further provided with two knob shanks 36 which extend through apertures in opposite sides of the lock case so as to position them end to end, they being held in position in any suitable manner.

The parts above referred to may be and preferably are of a well known construction.

In my improved lock as illustrated in the drawings, I provide a removable and reversible block 50 and two special hubs 38 mounted on the ends of the knob shanks 36 so as to be turned therewith when free to turn. These hubs are arranged side by side and each of them is provided with the usual upwardly extending tongue 40 that projects between the abutment lug 28 and the abutment plate 30 of the latch bolt, and is further provided with a forwardly extending hub lug 42, the lugs 42 being engaged by the spiral spring 44 having one end engaging both lugs and its other end secured to a post 46 on the casing, the same as in the usual two-hub lock. Each of the hubs 38 is, however, further provided with a rearwardly projecting stop lug 48 having its

end face arranged substantially in the plane of the upper face of the block 50, removably mounted in the lower rear corner of the lock case. This block 50 is held between 5 upstanding guiding members 52 adjacent the upper and lower faces of the block and is held from movement transversely of the lock case by a rib 54 cast on the bottom of the lock case and extending between said 10 members 52, the rib being received in one of the transverse slots 56 in opposed sides of the block. One of the corners of the block 50 is cut away so as to provide a recess 58, the cut-away portion being of a depth slightly 15 greater than the width of each of the hubs 38. The block 50 may be placed in three different positions in the lock case, or it may be entirely removed from the lock case. When the block 50 is placed in the position 20 illustrated in Fig. 3, in which the side thereof having the cut-away portion is opposite the upper one of the hubs 38 as shown in said figure, the knob shank associated with said hub may be turned so as to retract the 25 latch bolt, the cut-away portion of the block 50 permitting the stop lug 48 to clear the block. The stop lug 48 on the other hub 38, however, will, by engagement with the 30 side of the block 50, prevent the knob associated therewith from being turned in a direction to retract the latch bolt. By reversing the position of the stop block 50 so as to position the cut-away portion of the block opposite the stop lug 48 of the 35 last mentioned hub 38, as shown in Fig. 4, the knob associated with that hub may then be turned to retract the latch bolt, while the knob associated with the other hub will be held from turning. Thus it will be apparent 40 that by reversal of the latch bolt, and reversal of the pin tumbler lock from one side of the lock case to the other in the usual manner, that the lock may be used on either left or right hand doors, and that when thus 45 used either one of the knobs, usually the outer knob, may be held from turning movement while the other knob may be turned to retract the latch bolt, as desired.

In some cases it may be desirable to lock 50 both of the knobs from turning movement so that the latch bolt can not be retracted except by means of the roll back 14 of the pin tumbler lock. To accomplish this, the 55 stop block 50 is reversed in position so as to present the side opposite the cut-away portion 58 thereof to the stop lugs 48 of the hubs 38, as shown in Fig. 5, and when this is done it will be apparent that the stop lugs by engagement with the side of the

block will prevent both knobs from being 60 turned.

In some cases it may be desirable to permit the latch bolt to be retracted by either knob, the locking and unlocking of the door being accomplished entirely by the locking bolt 10. 65 This may be accomplished by entirely removing the stop block 50 so as to permit either one of the hubs 38 to be turned to retract the latch bolt, as shown in Fig. 6.

As will be evident to those skilled in the 70 art, my invention permits various modifications without departing from the spirit thereof or the scope of the appended claims.

What I claim is:

1. A lock having, in combination, a latch bolt, two hubs mounted side by side and arranged to retract said latch bolt when turned in one direction, and controllable means for preventing turning movement of either one or both of said hubs in said direction. 75

2. A lock having, in combination, a lock case, a latch bolt, knob shanks arranged end to end, a hub mounted on each of said shanks and arranged to retract said bolt upon turning movement of the shank associated therewith in one direction, and a stop member 85 removably mounted in the lock case and adapted to be positioned to co-operate with a part of either of said hubs to prevent 90 turning movement of either of said hubs in said direction, said lock case having an abutment preventing longitudinal movement of said stop member. 95

3. A lock having, in combination, a lock 100 case, a latch bolt, knob shanks arranged end to end, a hub mounted on each of said shanks and arranged to retract said bolt upon turning movement of the shank associated therewith in one direction, a stop member adapted 105 to be placed in three different positions within the lock case when in one of said positions co-operating with a part of one of said hubs to prevent turning movement thereof but permitting turning movement of the other hub in said direction, when in another of said positions co-operating with a part of the second mentioned hub to prevent turning movement thereof but permitting turning movement in said direction of the first 110 mentioned hub, and when in the third position co-operating with said parts of both hubs to prevent turning movement of either of them in said direction. 115

In testimony whereof, I have signed my 115 name to this specification this 1st day of Aug., 1925.

ERNEST L. TEICH.
